DESIGN FOR A SHADE FOR LIGHTING FIXTURES

Edward F. Cleary, Waterbury, Conn., assignor to Chase Brass & Copper Co. Incorporated, Waterbury, Conn., a corporation

Application August 6, 1938, Serial No. 79,167

Term of patent 7 years

To all whom it may concern:

Be it known that I, Edward F. Cleary, a citizen of the United States, residing at Waterbury, in the county of New Haven and State of Connecticut, have invented a new, original, and ornamental Design for a Shade for Lighting Fixtures, of which the following is a specification, reference being had to the accompanying drawing, forming part thereof.

Fig. 1 is a view in side elevation of a shade for lighting fixtures showing my new design; and

Fig. 2 is an underside view thereof.

The shade for lighting fixtures embodying my novel design is characterized by a conically-contoured lower portion producing an angular effect and surmounted by an upper portion having a concaved exterior surface leading upwardly and outwardly therefrom.

I claim:

The ornamental design for a shade for lighting fixtures, substantially as shown and described.

EDWARD F. CLEARY.
